UNITED STATES PATENT OFFICE.

CHARLES BREWSTER STEELE, OF NEW YORK, N. Y.

CONVERTIBLE CAR.

1,329,440.

Specification of Letters Patent.

Patented Feb. 3, 1920.

Application filed April 4, 1919. Serial No. 287,450.

To all whom it may concern:

Be it known that I, CHARLES BREWSTER STEELE, a citizen of the United States, and resident of the city, county, and State of New York, have invented a new and useful 5 Convertible Car, of which the following is a specification.

My invention is a convertible passenger car, of strong, practical and safeguarding 10 construction, having window openings approximately extensive from the carlines to the car floorings, within which the mere lowering of the sash instantly transforms the vehicle into a weather sealed storm 15 proof "winter car", or the simple raising of the sash reconverts the vehicle into a wide open air-penetrating "summer car." A single car thus capable of delivering reliable operative service of "two cars in one," 20 and insuring protective efficiency and dependable schedule in all kinds of weather and temperatures during every day of the year, will enable railways to eliminate and dispense with the use of a double equipment 25 of separate and distinct "winter" and "summer" rolling stock, and constitute a potential factor in the economic solution of first cost investment, maintenance, operative, and overhead expenses and their relation to 30 earning capacity and "fare" charges. Every moment that a car is not operating in scheduled service, it is a "dead asset"; actuary statistics affirming that street car riding is restricted during cold and inclement weather to necessity and expediency, 35 but that during warm and clement weather "pleasure riding" so greatly increases passenger traffic that the open "summer car" has been found the best earning asset of a 40 "road."

Another object of my invention consists in the construction of strong barrier guards for the window openings that protect the sash from damage when the sash are in lowered position, with free vision therethrough, but when the sash are in raised position safely guard passengers against the dangers and accidents of collisions, flying missiles, or the protrusion of persons, 45 their heads, limbs, and clothing, while affording a free circulation of air throughout the car; the complete conversion to or from

a closed or wide open car, being instantly and easily accomplished by passengers, conductor, or motorman, while the car is traveling at any rate of speed without interference with its operation or schedule.

Another object of my invention consists in constructing each of the underframe side sills of plural parallel members, spaced apart, and seating and clasping the uprights therebetween, thereby obviating the cutting and mortising of uprights; increasing the strength and rigidity of the car structure, and enabling the uprights, sash, or guards to be conveniently, expeditiously and economically repaired or replaced by the removal and readjustment of a few bolts and fastenings, permitting the quick return of the car to operative service and 70 schedule.

Another object of my invention consists in increasing the rigidity of the body structure by linking and bracing one upright with another from end post to end post 75 along the longitudinal axis of the car body at a suitable distance above the car flooring, so that such side braces may perform the double function of strengthening the car framing and form comfortable arm rests 80 for passengers when the window openings are in either raised or lowered position.

Another object of my invention consists in securing the sill flanges of each platform knee to the inner member of each of the 85 plural parallel side sills, thereby obtaining a stronger anchorage of the knees with increased underframe strength and rigidity, enabling the disposal of the knees at any desired point relative to the end sills 90 with less curvature of knee elbow distance intermediate the stirrups and knee sill flanges.

Figure 1 is a longitudinal elevation of a type and design of a car such as disclosed 95 in my copending application Serial Number 282,880, renewed Mar. 15, 1919, now Patent #1,308,511, issued July 1, 1919, showing window openings, between the uprights extending from the roof eaves to the car 100 flooring, within which are sash movably operative to raise and lower. Openwork barrier guards are shown across the window openings protecting the persons, heads,

limbs, and clothing of passengers from protrusion and danger when the sash are in raised position, and protecting the sash from damage when the sash are in lowered position, the double functional longitudinal and structural brace-arm rest being designated in dotted lines behind the lowered sash, and in full lines in the rear of the open work barrier guards.

10 Fig. 2 is a sectional elevation on line 2-2 of Fig. 1, showing a window opening having the sash therein in lowered position and protected from damage by an open-work barrier guard, on one side of the car, 15 with the window-opening entirely exposed by the sash being in raised position within the roofing, and the entirely exposed window-opening protected by the open-work barrier guard for safeguarding passengers 20 from danger, on the other side of the figure, with the brace-arm rest shown at convenient average height above the passenger seat.

Fig. 3 is a fragmentary cross section showing a window-opening with the sash in lowered position, protected by an open-work barrier guard, the exterior section of the guard protecting the sash from without, while its interior section protects the sash against damage from the feet and bodies of 30 passengers or otherwise, from within.

Fig. 4 is a fragmentary cross section showing sash in lowered position in a window-opening, with the exterior section of the open-work barrier guard ending at the level 35 of the brace-arm rest, its interior section movably operative, and a connective fixture mutually operative to facilitate the raising and lowering of the interior barrier guard section with the sash, and the brace-arm rest 40 located at a suitable distance above the car flooring.

Fig. 5 is a fragmentary cross section showing the sash in lowered position with a barrier-guard movably operative section in 45 raised position above the level of the brace-arm rest, and "non-frangible," transparent material forming the translucent portion of the sash.

Fig. 6 is a fragmentary cross section of a 50 window-opening in lowered position and employing a "non-frangible" material therein, with an interior barrier guard for protecting passengers when the sash are in raised position.

55 Fig. 7 is a modification of a fragment of a car, in elevation, showing substantially the same elemental features of Fig. 1; the lower sash section formed of an opaque panel and the window-opening terminating at a 60 point above the car floor, which is indicated by dotted lines, and the brace-arm rest designated in full lines across the exposed window-opening.

Fig. 8 is a fragment of a side elevation of 65 a car showing the sash in lowered position;

with a movably operative guard section indicated by dotted lines and lowered to the top level of the brace-arm rest.

Fig. 9 is a fragmentary cross section projection of Fig. 8 showing the sash and movably operative barrier guard in lowered position to the car flooring and top of brace-arm rest.

Fig. 10 shows a modified cross section with an opaque panel substituted for a lower sash 75 section, having a top sill, and a modified movably operative upper barrier guard section.

Fig. 11 is a perspective fragmentary view of one end of a plural parallel side sill and 80 an end sill, showing the arrangement of seating and clasping window frame uprights therebetween, with a platform knee secured to the inner section of the side sill.

Fig. 12 is a top plan view of Fig. 11.

Fig. 13 is a fragmentary elevation of a car showing window-openings with the sash in lowered position and protected by barrier guard sections front and rear up to the level of the brace-arm rests, and the movably operative barrier guard section in raised position above the brace-arm rest.

Fig. 14 is a fragmentary perspective of a portion of the combinative longitudinal uprights brace and arm-rest of angle bar construction with suitable arm-rest covering material, showing a method of notching and clasping the brace-arm rest to the window-uprights.

Fig. 15 is a fragmentary perspective of 100 two uprights and their longitudinal brace-arm rest, showing the brace-arm rest fittingly clasping the uprights, when constructed of materials such as wood.

Fig. 16 is a fragmentary cross section of 105 the plural parallel side sill with an upright seated and clasped therebetween, and braced and secured by angle iron brackets and angle bar stiffeners.

Fig. 17 is a fragmentary perspective of a 110 portion of a plural dual parallel side sill, and an upright, showing the angle iron securing brackets, angle bar stiffeners, and heating radiators within housings between uprights, produced by the plural dual side 115 sills, all of which is hereinafter more fully described in the specification, designated in the claims, and illustrated in the accompanying drawings, in which like numerals represent like parts in the different figures respectively.

The numeral 1, represents a passenger car, conforming to general standard design, but of such type as shown in my copending application, Serial Number 282,880, renewed 125 March 15, 1919, now Patent #1,308,511, issued July 1, 1919; numerals 2 and 3 designating ingress and egress doors, and 4 the body portion of the car, respectively.

Protracted window openings, 5, extend 130

approximately from the car roof eaves to the flooring within which movably operative window sash, 6, 7 and 8, are raisable within the roofing, or are lowerable to the 5 window-sills, 9, located at the floorline, as shown in Figs. 1, 2 and 3, when the dual parallel type of side-sills, 10, and 11, are used, but window sills may be located at short distance above the floorline should it 10 be desirable to utilize side-sill construction such as designated by numeral, 12, shown in Figs. 7, 8 and 9, or other sidesill structure suitable to subserve the purpose of extensively protracted window openings may 15 be substituted. The sash, 6, 7 and 8, are suitably operative to completely expose the window-openings, 5, thereby converting the vehicle into a wide-open "summer car," or reversibly operative to reconvert the vehicle 20 into a completely closed storm and weather-proof "winter-car", by means of transparent sectional sash, providing light throughout the openings when in closed position, but any other type of sash, or closures may be 25 employed, and the closures may slide, fold, buckle, or otherwise adjustably close or expose the openings, 5, and still preserve the broad principle of my invention, Barrier guards 13, of any suitable construction and 30 secured, preferably openwork, extend across the window-openings, 5, from the window-sills, 9, to a convenient height, but preferably of such range and sufficiency to protect and safeguard passengers from dangers 35 and accidents incidental to flying missiles, or protrusion of their heads, bodies, limbs, and clothing when the sash, or closures, are positioned to expose the window-openings, the barrier-guards, 13, also, permitting and enabling the sash, or closures, to be moved and adjusted to any desired position of their own sphere of operation without interference or contacting with the brace-arm-rests. 40

The numeral, 15, denotes the car flooring, laid suitably convenient of the side-sills, when the dual side-sills, 10 and 11 are used, and the window-sills, 9, are located to permit the openings, 5, to extend down to the 45 car flooring, 12, designating a side-sill construction providing means for accommodating window-openings at different distances above the floorline.

The numeral, 16, represents a device, suitably attached to the frame, provided with a cam lug 17, having suitable mechanical construction, such as, for instance, springs or passers, that will enable its engagement with the lug, 18, suitably located and fixed 50 on the guard, 20, so that when the sash is raised the device 16, would engage with the lug, 18, and raise the guard, 20, to the desired limit of its grooveway, the thus enforced stoppage of the guard, 20, causing 55 the mechanism of the device, 16, to operate the lug, 17, to disengage and pass the lug, 18. The lowering of the sash similarly operates the mechanism controlling the lug, 17, to pass the lug, 18, and then contact with 60 the lug, 19, and carry the guard, 20, with the sash down to the sash sill to its position when the opening is weather sealed, and while several forms of stationary and 65 movable barrier guards, and a type of mutually 65 engaging and operating means is shown in the drawings, any type of guards or latching, unlatching, locking, unlocking, engaging, disengaging, or passing means, or mechanical device may be utilized to impart a 70

guards may be constructed in sections protecting both the exterior and interior surfaces of the sash, or closures, as illustrated in Fig. 3, and the barrier guards may be stationary or movable, all without departing from the broad principle of my invention comprising a car completely convertible and reconvertible, vice-versa, from a thoroughly closed storm and weather proof "winter car", to a wide-open air circulating 75 "summer-car" by the mere raising or lowering of the sash, or closures. 80

Braces, 14, extend along the sides of the car-body across the window-openings, secured to and linking the window-uprights to one another, so greatly increasing the rigidity of the car throughout the belt-line region that the strength of the entire plan structure to resist stress and strain is superior to cars not provided with extensively 85 protracted window-openings; the braces, 14, also, combining and performing the double function of comfortable arm-rests for passengers, located at the convenient approximate height of the belt-line, and thereby 90 permitting and enabling the sash, or closures, to be moved and adjusted to any desired position of their own sphere of operation without interference or contacting with the brace-arm-rests. 95

The numeral, 15, denotes the car flooring, laid suitably convenient of the side-sills, when the dual side-sills, 10 and 11 are used, and the window-sills, 9, are located to permit the openings, 5, to extend down to the 100 car flooring, 12, designating a side-sill construction providing means for accommodating window-openings at different distances above the floorline.

The numeral, 16, represents a device, suitably attached to the frame, provided with a cam lug 17, having suitable mechanical construction, such as, for instance, springs or passers, that will enable its engagement with the lug, 18, suitably located and fixed 105 on the guard, 20, so that when the sash is raised the device 16, would engage with the lug, 18, and raise the guard, 20, to the desired limit of its grooveway, the thus enforced stoppage of the guard, 20, causing 110 the mechanism of the device, 16, to operate the lug, 17, to disengage and pass the lug, 18. The lowering of the sash similarly operates the mechanism controlling the lug, 17, to pass the lug, 18, and then contact with 115 the lug, 19, and carry the guard, 20, with the sash down to the sash sill to its position when the opening is weather sealed, and while several forms of stationary and 120 movable barrier guards, and a type of mutually 125 engaging and operating means is shown in the drawings, any type of guards or latching, unlatching, locking, unlocking, engaging, disengaging, or passing means, or mechanical device may be utilized to impart a 130

coactive operative movement of the sash and guards, and any desired type of sash and method of their movement, displacement, raising, lowering, or housing may be 5 employed, and the guards may be fixed, moved or operated individually, or by coactive means, or any other modification made and employed in the construction and operation of the sash and guards, without 10 departing from the intent, purpose, spirit and broad principle of my invention, which comprises both in its parts and its entity the practical, economic, efficient, standardized production of an ever ready, really, 15 fully, and completely convertible car, that can be instantaneously converted from a "winter" car to a "summer" car, or vice versa; that includes equal completeness in either of its forms of conversion, thereby 20 providing a safe, comfortable, pleasant, and enjoyable means of transportation for every day in the year, during all varieties of weather and conditions of maintenance and operation.

25 In Fig. 5 is shown a modification in which the exterior guard is omitted, with an interior guard, 23, for the protection of the interior surfaces of the sash glass when the window openings are sealed, and for the 30 protection of the lower portion and limbs of passengers when the window openings are unsealed, the guard, 24, being movably operative to a raised position above the arm rest, 25, when the window openings are 35 unsealed to protect the upper portion of the bodies of passengers, and movably operative to be lowered to a position level with the top of the arm rest, 25, and between the guard section, 23, and the interior surface 40 of the sash, when window openings are sealed.

In Fig. 6 is shown a modification in which the interior guard, 26, is stationarily located to protect the heads, limbs, and clothing of 45 passengers when the window opening is unsealed, and protect the sash from the feet and limbs of passengers when the window opening is sealed by the sash.

In Fig. 7 is shown a modification of a 50 fragment of a car body, 28, with translucent sash weather sealing two window openings, a lower sash section, 29, having opaque panel portions, 30, and 31. The exposed window opening, 32, is protected by the 55 guard, 33, which is shown in its raised position that protects the heads, limbs, and clothing of passengers from protrusion, the brace-arm rest, 14, showing through the screenwork, and car wall, 35, extending 60 above the floor line, 36, indicated by the dotted line, 37, the exterior guard being omitted.

In Fig. 8 is shown fragmentary modification of Fig. 7, in projection thereof, 65 showing the window opening weather sealed

by glass sash, and the guard, 38, shown by dotted lines in its lowered position extending from the brace-arm rest to the floorline along the inner side of car wall, 39, the lower sash section being transparent.

70

In Fig. 9 is shown a cross section, broken away, on the projection of Fig. 8, showing the window opening sealed by glass sash, 40, the protective barrier guard, 41, in lowered position protecting the sash glass, and its 75 groove, 42 into which it is raised when the opening is exposed.

In Fig. 10 is shown a modification substituting solid opaque lower sash sections, 43, having sash sills, 44, upon which the sash sections 7 weather sealingly rest and fit, the sash sections, 7, and 8, being provided with combinative detachable hinge fixtures, 45, that permit the transparent sash sections, 8, to be detached from the sections 7, and be removed from the car, if desired, in "winter" time, and solid opaque sections, 43 substituted therefor and adjusted immovably in the openings, to form, for instance, the equivalent of solid side 90 walls for that portion of the car body, during the cold weather period, the movably operative sash sections, 6, and 7, thence forming the car windows. The lower interior safety-guard, such, for instance, as 95 shown in Fig. 5, and designated by the numeral 23, would, also, be removed, and the guard, 46, that reciprocates in the groove, 47, of Fig. 10, would be utilized to protect the heads and upper portion of the 100 bodies of passengers from danger and protrusion, or protective barrier guards such as designated, for instance, by numeral 13, in Fig. 3, or by numeral 26, in Fig. 6, may be utilized when the sash sections 43, are thus 105 employed, or the opaque lower sash panel section, 43, may be unfixed, or may be hingedly adjusted to move and operate with the sash sections, 6, and 7, or any other suitable means may be employed for guarding unsealed window openings, should it be desired to use solid opaque lower sash sections susceptible of being unfixed, and removed from the car, such, for instance, as 110 shown and designated by the numerals 46, 115 and 48, in Fig. 10.

Side-sills, are shown in Fig. 11, formed of dual parallel plates, 49, and 50, spaced apart thus enabling the window-uprights, 51, and 52, to be made of uniform integrity, 120 and so rigidly seated within and between the sill plates and firmly clasped thereby, that the heretofore weakening of the uprights at their points of union with the side sills by notch and mortise joint cuttings 125 is eliminated, and by thus dually reinforcing the side-sills, a basic body sill foundation is formed that cannot sag, torque, nor bend under abnormal weight. The dual side sill plates may be stiffened by angle 130

bars, 61, and 62, secured to their inner or outer surfaces, and the side sill plates may be additionally trussed and secured together by any suitable means, such, for instance, as the clamping brackets, 53, 54, 55, and 56, bolts 57, and braces 63. The end-frame corners, and sides of the underframe are thus, also, materially strengthened to resist shock from collisions, and should the outer sill plate, 49, for instance, be subjected to such an extraordinary force of impact as to dent it, the spaced apart parallel inner plate, 50, would act as a warding buttress to the outer plate, 49, and prevent wreckage of the framing, and if the uprights were injured, the exterior plate, 49, and any of the uprights can be readily and easily removed, repaired, and replaced without disturbing the integrity of the balance of the car structure. Likewise the sash, barrier-guards, and various sections and parts of the underframe, and uprights may be detached and reattached, without detaching other elements of the construction.

The platform knee, 65, having its sill flange, 68, secured to the inner side of the plate, 50, and clamped therewith to the plate, 49, by the shoulder bolts, 69, permits shortening of the lateral bend of the knee elbow between the side-sill and the upholding stirrup, 65, and reduction of knee torque and weight stress. The sill may be constructed of dual plates, and stiffened by angle bars, 61, and 62, or may be dual angle pieces of unequal legs forming a bottom thereto, or girders, I beams, channels, or any style of models employed, and the end sills, preferably made of channels, may be seated, hung, or secured in any manner, or at any desired level relative to the side sills, it being designed to utilize trade stock models throughout the car construction.

In Fig. 13 is shown a portion of the side structure of a car body illustrating the employment of the strong sill construction disclosed in Fig. 11 that enables the protracted window openings to extend down to the sash sill, 70, with the sash shown in closed position sealing the window openings, and both sides of their glasses protected by the exterior and interior sections of the barrier guards, 13, and 13', while the unsealed and completely exposed protracted window opening, 5, has the reciprocating upper section barrier guard, 13', in raised position above the combinative upright brace-arm rest, 14, thereby protecting the bodies and clothing of passengers above and below the brace arm-rest, while permitting free vision and circulation of air therethrough.

In Fig. 14 is shown a perspective fragment of the longitudinal brace, 14, for rigidly staying and trussing the window uprights, or posts, and side frame structure, that also forms arm-rests between the up-

rights, modified in construction by the employment of a metal angle bar, 71, with joints, 72, made in its plan leg that fit around and clasp the uprights, while the perpendicular leg, 73, stretches in longitudinal continuity across the uprights, finished with a covering, 74, of wood, or other suitable material, upon which passengers' arms may rest.

In Fig. 15 is shown a perspective fragment of two window uprights, or posts, 75, joined and clasped by the longitudinal brace and arm rest, 14.

In Fig. 16 is shown a fragmentary cross section on line 16—16 of Fig. 12, of the dual parallel plates, 49, and 50, of a side sill, within which are seated and clasped uprights, 76, angle iron securing braces, 77, and angle bar stiffeners, 78, and 79.

In Fig. 17 is shown a fragmentary perspective view of the same constructive matter as that of Figs. 11, 12, and 16, with the angle bar stiffener modified by elongation of its lower leg, 80 to form a base for the inclosure, 81, providing housings for the radiators, 82, and 83, between the window uprights for heating the car, and though a Z stiffener, 63, is shown in Fig. 11, any type of bracing, trussing, or cross sills and bolsters may be utilized.

The problem of producing a car having a wide open side structure provided with the required strength and rigidity to resist twisting and torsional strain, and combining therewith convenient, simple, easy, and "fool proof" means of instant conversion, vice versa, to and from a completely closed or completely open vehicle, while insuring the absolute safety, comfort, and enjoyment of the riding public, is hereby practically solved and attained by the novel construction of dual membered side sills that permit the seating and clasping of the four uniform uncut surfaces of the window uprights within such socket inclosures; and the linking of the window uprights with one another and the corner posts by the longitudinal brace-arm rests, all thus coöperating to prevent sagging and wrenching of the car structure, additional passenger foot space being also provided by elimination of the heretofore objectionable interior side sill projection along the floor line of the car side walls, the reposition of heating, or other car auxiliaries, in the closures, 81, within the side-sills, thus, also ridding the interior of the car of conduits, radiators, ventilators, and other impedimenta that have hitherto inconvenienced and annoyingly obstructed the feet and limbs of passengers.

The modifications disclosed in the specification and various figures of the drawings are derivatives of the basic principle involved throughout the invention in all the views and comprises, includes and encom-

passes means of constructing cars having protracted openings extending approximately from the roof eaves down to the floorings, that are closable during cold or 5 inclement weather, and unclosable and exposable during warm or pleasant weather, with openings guarded and protected when open by means permitting free vision and circulation of air therethrough, while at the 10 same time the closable and unclosable means and the guarding means remain a constructive part of the car and operable with or without removal therefrom. Should it be desired to close or unclose the openings by 15 use of movably operative closing and opening means in connection or in coöperation with movably operative guarding means, such as shown, for instance, in Fig. 4, instead of stationary guarding means, such, 20 for instance, as shown in Figs. 1, 2 and 3, or otherwise, the same intrinsic essential of invention would be equally embraced and involved in any and all forms of constructions, means, or use, disclosed or not disclosed, and any other mode of construction, 25 means of disposition, or operation that will or may involve an equivalent, or produce the same results by the same means, or other means, may be utilized without departing 30 from the spirit and broad principle of my invention.

What I claim to be my invention, is:

1. A convertible car having openings therein, means closing and unclosing the 35 openings, and barriers shielding the bodies, limbs and heads of occupants of the car when the openings are unclosed.

2. A convertible car having openings provided with means closing and unclosing the 40 openings at any selective point thereof and barriers shielding the bodies, limbs and heads of passengers against dangers from without and protrusion from within when the openings are partially or wholly unclosed.

3. A car having openings therein provided with closures, arm rests dividing the openings, barriers above and below the arm rests, the car being convertible and convertible vice versa to and from a closed and open car by raising and lowering of the closures and the openings being shielded by the barriers when the closures are raised.

4. A convertible car having openings 55 therein provided with shiftable closures and shielding means above and below the car belt-line by which shifting of the closures produces an open or closed car and shields the openings.

5. A car having openings therein divided by arm rests, barriers shielding the openings above and below the arm rests and convertible means sealing and unsealing the openings by which shifting of the sealing 60 unsealing means converts and reconverts the

vehicle vice versa from and to a closed or open car.

6. A convertible car having roofing and flooring, openings extending approximately from the roofing to the flooring provided 70 with closable and unclosable means, and barriers shielding the openings and the closable-unclosable means above and below the car belt-line.

7. A convertible car having roofing and 75 flooring, openings extending approximately from the roofing to the flooring provided with closures closing and exposing the openings and barriers shielding the openings above and below the car beltline region when 80 the openings are exposed and simultaneously shielding the closures and the openings when the openings are closed.

8. A convertible car having openings 85 therein stretching above and below the car beltline region provided with closures sealing and unsealing the openings at any selective elevation of the closures, and barriers shielding the openings above and below the beltline region when the openings are sealed 90 or unsealed.

9. A convertible car having openings 95 therein above and below the car beltline region provided with members sealing and unsealing the openings, and barriers shielding the openings above and below the beltline region.

10. A convertible car having openings therein above and below the car beltline region provided with translucent sealing and 100 unsealing members and barriers shielding the openings above and below the car beltline region.

11. A convertible car having openings 105 therein above and below the car beltline region provided with translucent and opaque sealing and unsealing members and barriers shielding the openings above and below the car beltline region.

12. A convertible car having openings 110 therein, members closing and exposing the openings provided with attachable-detachable lower sections interchangeable with attachable sections having a sill member, and barrier, shielding the openings above and 115 below the beltline region of the car.

13. A convertible car having openings therein provided with transparent sealing and unsealing means and barriers shielding the bodies, limbs and heads of passengers 120 against dangers from without and protrusion from within when the openings are sealed or unsealed.

14. A convertible car having openings 125 therein provided with means closing and unclosing the openings at various closing and unclosing dispositions of the closing-unclosing means and barriers shielding both sides of closing-unclosing means when the openings are closed. 130

15. A convertible car having openings therein provided with means closable and unclosable throughout the openings at various dispositions thereof, and openwork 5 barriers shielding both sides of the closable-unclosable means when the closable-unclosable means is in closable disposition and shielding the openings when the closable-unclosable means exposes the openings.
- 10 16. A convertible car having openings therein provided with closing and unclosing means and barriers shielding the inside and outside of the closing-unclosing means when in closed disposition and shielding the openings when the openings are exposed.
- 15 17. A convertible car having openings therein, arm-rests dividing the openings, barriers shielding the openings above and below the arm-rests.
- 20 18. A convertible car having uprights divided by members forming upper and lower openings therebetween provided with closable-unclosable means and barriers shielding the upper and lower openings formed by 25 the dividing members.
- 30 19. A car having openings therein provided with braces functioning armrests dividing the openings into a plurality of openings above and below the braces, means closing and unclosing the openings and barriers shielding the openings above and below the braces.
- 35 20. A convertible car having roofing and flooring, openings extending approximately from the roofing to the flooring provided with means closing or unclosing the openings, and barriers shielding the openings when closed or unclosed above and below the car beltline.
- 40 21. A convertible car having openings therein provided with closing and unclosing means and barriers shielding the openings when the closing-unclosing means is unclosed and shielding the exterior and interior of the closing-unclosing means when 45 the openings are closed.
- 50 22. A convertible car having an opening therein provided with a closure sealing and unsealing the opening and a barrier having an external and an internal section shielding the closure when the opening is sealed and shielding the opening when the opening is exposed.
- 55 23. A convertible car having openings therein provided with closures closing and exposing the openings and barriers having movable and immovable sections shielding the closures when the openings are closed and shielding the openings when the openings are exposed.
- 60 24. A convertible car having openings therein provided with movably operative closures exposing or sealing the openings, barriers having movably operative sections 65 shielding the closures when the openings
- are sealed and shielding the heads, limbs, and clothing of occupants of the car when the openings are exposed, and fixtures connective of the closures and barriers imparting mutual coaction between the movably 70 operative closures and movably operative sections of the barriers.
25. A convertible car having protracted openings therein extending above and below the beltline of the car, closures sealing or exposing the openings, barriers shielding the closures when the openings are sealed and shielding the openings when the openings are exposed, arm-rests across the openings permitting functioning of the closures and 80 barriers independent and irrespective of the arm-rests.
26. A car having end-sills and side-sills each side sill formed of dual members spaced apart and secured at different points extensive of the end sills, a knee secured to the inner member of the side-sill and to the end sill thereby shortening the lateral leverage of the knee elbow and increasing the upholding strength. 90
27. A car having end-sills and side-sills each side-sill composed of dual members spaced apart, uprights secured between the dual members of the side-sills and heating apparatus within the dual members between 95 the uprights.
28. A car structure including roofing and flooring; side-sills formed of a plurality of members spaced apart; uprights supportingly clasped within the spaced apart side-sill members; openings protracting approximately from the roofing to the flooring between the uprights, and means closing and unclosing the openings protracting approximately from the roofing to the flooring. 100
29. A convertible car having roofing and side structure; an under structure provided with side-sills; window-openings in the side structure enabled by the side-sill arrangement to extend approximately from the side-sills to the roofing structure; sash closable and unclosable of the window-openings, and barriers shielding the heads and limbs of occupants of the car. 110
30. A convertible car having roofing and flooring; window-openings extending approximately from the roofing to the flooring; window-sills adjacent the flooring; sash closably and unclosably operative of the window-openings; armrests adjacent the window-openings, and barriers shielding the window-openings above and below the armrests. 115
31. A car construction including side-sills formed of members spaced apart; uprights seated and clasped between the spaced apart side-sill members; braces trussing the spaced apart side-sill members to one another and clasping the uprights, whereby open spaces are formed between the spaced 125
- 130

- apart side-sill members extending from a brace clasping an upright to a brace clasping another upright.
32. A car structure provided with side-sills each formed of a plurality of members spaced apart having flat surfaces opposing each other, members therebetween bracing the spaced apart members to one another thereby mutually forming a plurality of sockets within the spaced apart members and uprights securely clasped and gripped by and within the sockets.
33. A convertible car having openings therein; means closing and unclosing the openings below the car beltline region; means closing and unclosing the openings above the car beltline region, and means shielding the openings both above and below the car beltline region.
34. A convertible car having openings therein: opaque means closing and unclosing the openings below the car beltline region; transparent means closing and unclosing the openings above the car beltline region, and means shielding the openings both above and below the car beltline region.
35. A convertible car having openings therein provided with means approximate the car beltline region dividing the openings into a plurality of openings; means closing and unclosing the openings below the car beltline region dividing means; means closing and unclosing the openings above the car beltline region dividing means, and means shielding the openings both above and below the car beltline region dividing means.
36. A car structure including side-sills each formed of a plurality of members spaced apart, and platform supports secured interiorly of the members of the spaced apart plurality of side-sill members.

CHARLES BREWSTER STEELE.
